(57) **CLAIM**

The ornamental design for a coffee cup lid, as shown and described.

DESCRIPTION

FIG. 1 is a top perspective view of a coffee cup lid showing the new design;

FIG. 2 is a bottom perspective view of FIG. 1;

FIG. 3 is a top plan view of FIG. 1;

FIG. 4 is a side elevational view of FIG. 1; and,

FIG. 5 is a bottom plan view of FIG. 1.

Broken lines depict the boundary of the claim and form no part of the claim.
